Atty.

UNITED STATES PATENT OFFICE.

CHARLES E. BRAINARD, OF CHICAGO, ILLINOIS.

PULVERIZING-MACHINE.

1,360,364.

Specification of Letters Patent. Patented Nov. 30, 1920.

Application filed January 8, 1920. Serial No. 350,159.

To all whom it may concern:

Be it known that I, CHARLES E. BRAINARD, a citizen of the United States, residing at Chicago, in the county of Cook and State 5 of Illinois, have invented certain new and useful Improvements in Pulverizing-Machines, of which the following is a specification.

This invention relates to improvements in 10 pulverizing machines.

One of the objects of the invention is to provide an improved rotatable machine for continuously pulverizing granulated material.

15 Another object is to provide a machine in which a loose revoluble, floating weight, carried by an inclosing, rotatable casing; provides tapered passage ways between its crushing surfaces and the confronting surfaces 20 of the casing to contain the material acted upon, in graduated sizes, whereby to provide continuous crushing operation of the machine.

Another object of the invention is to provide 25 renewable crushing surfaces for the casing and means for adjusting the surfaces with respect to coöperating surfaces.

Other and more particular objects of the invention will become readily apparent to 30 persons skilled in the art, from a consideration of the following description when taken in conjunction with the drawings, wherein:

Figure 1 is a longitudinal section taken on 35 line 1—1 of Fig. 3.

Fig. 2 is a section taken on line 2—2 of Fig. 1.

Fig. 3 is a section taken on line 3—3 of Fig. 1.

40 In all of the views the same reference characters are employed to indicate similar parts.

5 is a cylindrical part or sleeve of the casing, expanded at its inner end to provide 45 a part 6 which forms a member of the crushing casing. 7 is another member of the crushing casing, having an axial opening, as at 8, and secured to the member 6 by bolts 9. Located inside of the 50 casing, composed of the parts 6 and 7, is a ring 10 of suitable, refractory material, that is inherently hard, or hardened by any process, necessary to withstand the attrition of the material being pulverized. 11 is a ring, 55 or gasket, placed in the member 7 and adapted to be reduced in thickness, to provide, in

coöperation with the bolts 9, means for adjusting the distance of separation between the parts 6 and 7 to compensate for wear. Located in the tapered sides of the casing 60 are wearing rings 12 and 13, held therein by suitable means, such as bolts 14. These rings are of material similar to that of which the ring 10 is composed, and so arranged that the radially directed surfaces 65 converge toward each other, to provide a tapered opening therebetween. Located in the crushing chamber, between the members 6 and 7 is a tapered weight or floating ring 15, somewhat smaller in diameter, and of 70 preferably ring form, having an axial opening 16. The weight is loose in the composite casing having no connection therewith except as a result of the effect of gravity. The weight or ring is made of a hardened 75 material or has its surfaces case hardened or tempered to withstand the abrading effects of the material for which it is employed to crush. The weighted ring 15, rolls around in the casing as the latter is 80 revolved, and the sides of the ring being tapered, the crushing effect is produced between the tapered sides of the ring and the inclined hardened rings 12 and 13, and also between the end of the crushing ring 15 85 and the replaceable ring 10 of the casing. That the material may more conveniently find its way between the crushing surfaces of the crushing member, I may provide tangentially inclined grooves 17, in the tapered 90 face of the ring 15, to convey the material from the opening 16, of the ring, to points nearer its peripheral surface. Since there is a tapering space 18 on each side of the axis of the ring 15 and between its peripheral surface and the confronting surfaces of the rings 12 and 13, this, in most instances is sufficient to distribute the material and, therefore, in some instances the tangential 95 grooves 17 will not be necessary.

100 The revolving casing is supported by the sleeve, or hollow cylinder 5, in bearing 20 provided on the base 21. A gear wheel 22 is secured to the sleeve, or cylinder 5, for the purpose of rotating the casing.

105 A pipe 23 is secured to a flange 24 that is located upon the end of the sleeve 5, and within which the sleeve rotates. The pipe 23 is for connection with an air moving exhaust fan or water pump to induce a draft 110 of air or stream of water through the pulverizing machine. Located inside of the

cylinder 5 are a series of spaced apart, inwardly extending abutments 24, in the form of screw threads, and extending spirally through the cylinder so that any relatively heavy material that may find itself within the cylinder will lodge behind the blades and be carried upwardly by the rotation of the device, when it will drop between contiguous abutments that are inclined toward 10 the crushing portion of the casing and finally will find its way back into the casing, there to be crushed.

Abutments 25 are located in the opening 8, of the crushing casing, so as to direct the material that may fall thereon into the interior thereof. A hopper 26 is located above a chute 27 having its inner end introduced into the opening 8, by which the material to be crushed is led into the crushing casing. A valve, or door 29, is hinged to the discharge end of the opening into the casing so as to serve as means for regulating the flow of material therein.

While I have herein shown a single em-

bodiment of my invention, for the purpose 25 of clear disclosure, it will be manifest, to persons skilled in the art, that considerable variation in configuration and disposition of the parts may be made within the scope 30 of the appended claim.

Having described my invention what I claim as new and desire to secure by Letters Patent is:—

A machine of the character described having in combinative association a rotatable two-part casing with two removable, radially converging, crushing side members therein; means to adjust the casing members to compensate for wear of the side members, comprising a ring adapted to be reduced in thickness and bolts holding the said casing members together against the ring and a tapered crushing ring, having radially converging side surfaces, floating 40 within said casing.

In testimony whereof I hereunto subscribe my name.

CHARLES E. BRAINARD.
